UNITED STATES PATENT OFFICE.

HERMAN F. HOEVEL, OF NEW YORK, N. Y.

SPRAYING DEVICE FOR RIMS AND OTHER ARTICLES.

Application filed December 24, 1921. Serial No. 524,624.

My present invention has for its object to provide a convenient and readily operated device for spraying rims or other articles with sand (sand-blasting them) or other 5 cleaning or treatment agent. The invention comprises a support for bringing said articles into and out of the field of action of nozzles which project the agent against such articles, and also includes means located partly on said support and partly on a stationary structure, for moving the articles relatively to the said support while exposed to the agent sprayed or projected toward said articles, so that different portions of said articles will be exposed successively to the action of such agent. The invention also consists of other novel features which will be explained in the description following hereinafter, the scope of the invention being 20 indicated in the appended claims.

Reference is to be had to the accompanying drawings illustrating two satisfactory examples of my invention. Fig. 1 is a plan view of one form of my invention, with parts 25 in section; Fig. 2 is an elevation with parts in section substantially on line 2—2 of Fig. 1; Fig. 3 is a vertical section substantially on line 3—3 of Fig. 1; Figs. 4 and 5 are partial views similar to Figs. 2 and 1 respectively, illustrating another embodiment of my invention.

In both forms illustrated, 10 indicates the side walls and 11 an end wall of a building in which the sand-blasting or other operation 35 is to be performed. In said end wall is provided an opening 12, generally of rectangular shape (see Fig. 3) adapted to be substantially closed at times by a vertical wall or partition 13 extending upward along a diameter of a turntable 14 the center of which is in line with said end wall, at the center of the opening 12. This turntable forms a support for the articles to be treated, and it will be understood that one-half 45 of the turntable projects exteriorly of the building, so that this half may be readily loaded with the articles, when the partition 13 is in line with the end wall 11 as illustrated in the drawings. By giving the turn-

table a half revolution, the articles previously placed thereon are carried into the building, and into co-operative relation to the nozzles and other devices, as will be explained below, the partition 13 again swinging to a position to fit the opening 12 and to 55 reduce the escape of dust, sand, etc., from the building during the operation. The turntable 14 may be supported and rotated in any suitable manner, for instance by making it run on rollers 15 journaled in stationary bearings 16, and by placing on the shaft 17 of the turntable, a spur gear 18 in mesh with a spur pinion 19 on a shaft 20 driven by bevel gearing 21. The turntable 14 preferably has openings so that the sand or other 60 agent may fall into a hopper or trough 22 at the bottom of which I have indicated a rotary screw conveyor 23 for carrying the sand away to a place where it will be picked up by elevators or disposed of in any other well-known or approved manner. 70

Above the level of the opening 12 and of the partition 13 I have indicated a horizontal overhead track 24, parallel to the end wall 11, and on said track is adapted to travel a carriage 25 having one or more nozzles 26, with pipes 27 or other connections for supplying air and sand (or other agents) to said nozzles. 75

At one side of the building I have indicated at 28 an electric motor or other suitable device for driving a shaft 29 which within a box or casing 30 carries a worm 31. So far as described, both forms of my invention are substantially alike. 80

In the form illustrated by Figs. 1, 2 and 3, the worm 31 is in mesh with a worm-wheel 32 on a transverse shaft 33 extending into the building, close to the path of the turntable 14. The latter is provided with two pairs of 90 horizontal rollers 34, the axes of which are parallel to the diameter along which the partition 13 is arranged, and the pairs of rollers are arranged on opposite sides of said partition, at equal distances therefrom. At opposite ends of the two pairs, the ends of the rollers 34 carry sprocket wheels 35, the two wheels 35 of the same pair being connected 95

- by a chain 36 which also engages a sprocket wheel 37 on a short shaft 38 carried by the turntable between the roller axes, and preferably at a higher level. These short shafts 5 extend outwardly, toward the edge of the turntable 14, and are provided at their outer ends with clutch members 39 adapted to be engaged with a mating clutch member 40 at the inner end of the shaft 33, it being understood 10 that the shafts 33 and 38 are located at the same level and that the shaft 33 is arranged to align with one or the other of the shafts 38 whenever the turntable 14 has its partition 13 in line with the opening 12 of the end wall 11, see Fig. 1. While the shaft 33 is coupled to one of the shafts 38 and rotates this shaft 38 together with the corresponding rollers 34 and articles, such as rims 41, resting on said rollers, the carriage 25 is made to travel along the track 24, in a direction parallel to the said rollers 34 and about centrally over the rims 41 or other articles so as to thoroughly sand-blast or otherwise treat the said articles. It will be understood 20 that a large number of such articles may be placed side by side on the rollers 34. While one set of articles is thus being treated on the rollers 34 which at that time are within the building, the other pair 30 of rollers 34 is outside the building and therefore readily accessible for removing the articles previously treated, and for placing a new set of articles on such pair of rollers. The operation within the building having been completed, the shaft 38 is disconnected from the shaft 33, the turntable is given half a revolution, and the shaft 38 is coupled to the other shaft 33 which has thus been brought into the operative position. 35 In the construction illustrated by Figs. 4 and 5, the rims or like articles 41, instead of resting with the lower portion of their outer peripheries on rollers such as 34, have the upper portions of their inner peripheries in contact with rollers 42, of which there is only one on each side of the partition 13, the axes of these rollers 42 being in the same general relation to the turntable as the shafts 33, that is to say, each of these rollers is 40 adapted to align, after the turntable has been rotated successively through angles of 180°, with the transverse drive shaft 33' carrying a worm wheel 32' in mesh with the worm 31. The shafts 43 of the rollers 42 are 45 provided at opposite ends with clutch members 39' for co-operation with the clutch member 40' on the shaft 33'. In both forms of my invention, the clutch connections 39, 40 and 39', 40' have been indicated only 50 grammatically, since clutch devices for coupling and uncoupling aligning shafts are well-known. The second form of my invention is somewhat simpler in construction than the first, but generally requires the rollers 42 to be temporarily removed from 65 their bearings in order to allow the rims or other annular articles 41 to be placed in position on said rollers.
- I claim:
1. An apparatus of the character described, comprising a building with an opening in one of its walls, a turntable having a diametral partition to fit said opening, means carried by said turntable and rotatable relatively thereto, to support and revolve articles to be treated, such means being provided in duplicate, on opposite sides of said partition and at equal distances therefrom, a drive shaft journaled in stationary bearings and into operative relation to which one or the other of said article-revolving means on the turntable is adapted to be brought by the rotation of the turntable, and means for coupling and uncoupling said shaft to and from said article-revolving 80 means. 75
2. An apparatus of the character described, comprising a building with an opening in one of its walls, a turntable having a diametral partition to fit said opening, means carried by said turntable and rotatable relatively thereto, to support and revolve articles to be treated, such means being provided in duplicate, on opposite sides of said partition and at equal distances therefrom, and power-operated means located within said building with which one or the other of said article-revolving means is brought into operative alignment by the rotation of the turntable only when said partition is located within 100 and completely closes said opening. 95
3. An apparatus of the character described, comprising a movable support, means carried by said support and rotatable relatively thereto, to support and revolve articles to be treated, a nozzle-carriage for co-operation with said articles, a rectilinear track for said carriage, and stationary power-controlling means adapted to be brought into operative relation to said article-revolving means by the movement of the support to a position in which said article-revolving means is in operative relation to the nozzle-carriage. 105 110
4. An apparatus of the character described, comprising a turntable, means carried by said turntable and rotatable relatively thereto, to support and revolve articles to be treated, stationary power-controlling means, adapted to be brought into and out of operative relation to said article-revolving means by the rotation of the turntable, a stationary track which is parallel to the axis of rotation of said articles at the time said power-controlling means is in operative relation to said article-revolving means, and a nozzle-carriage arranged to travel on said track. 115 120
5. An apparatus of the character de-

scribed, comprising a turntable rotatable about a vertical axis, article rotating means mounted on said turntable, comprising rollers rotatable upon a horizontal axis, means for 5 projecting a spray of material on said articles, said spray projecting means being movable along a horizontal line above said turntable, means for rotating said turntable to bring the articles to be treated into alignment with the spray projecting means and 10 stationary power-controlling means including a clutch, into alignment with which said article rotating means is adapted to be brought only when the articles to be treated are located in alignment with the line along 11 which said spray projecting means is operative.

In testimony whereof I have signed this specification.

HERMAN F. HOEVEL.
